Design No 599—

M. Lachenmaier's
Design for a Wire Fence.

Patented November 21, 1854.

Mathias Lachenmaier, of Philadelphia, Pa.
Letters Patent No 679 Dated Nov. 21st 1854

The schedule referred to in these Letters Patent and making part of the same

To all whom it may concern:

Be it known, that I, M. Lachenmaier, of the City of Philadelphia, and State of Pennsylvania, have invented or produced a new and original design for a wire fence, and I do hereby declare that the following is a full and exact description of the same, reference being had to the annexed drawings making a part of this specification.

The nature of my invention consists in combining together short pieces of wire as to produce a row or rows of horizontal twists both above and below a horizontal row or rows of rosettes adapted to hold and bind together the wires between the rails.

The drawing represents two rows of three twists as arranged and combined with one horizontal row of rosettes, the wire ends being secured by riveting in the usual manner to the top and bottom rails.

A represents the horizontal twists; B, the rosettes; C, C, the top and bottom rails, and D, one of the vertical pieces. Each of the twists (A) are formed by twisting together two pieces of short wire, whilst red hot, and then bending the projecting ends so as to adapt one pair of them (a, a) for combination with the rosettes (B) and the other pair (b, b) with the rails (C, C) or, when desired with other like horizontal rows of rosettes. The rosettes are made in two parts (c, c,) concave on the inside and with suitable openings (d) on each of the four sides or edges thereof, for the admission therein of the ends (a) of the wires, and so as to be secured firmly together by means of a rivet (e) through the holes

22

in the center of the two pieces, after the ends (a) of the wires are placed between them, as shown in the drawings. The opposite ends (b) of the wires are each secured in suitable holes made through the rails as shown by the dotted lines at f, or in like manner as described, with other horizontal rows of rosettes, when more than one row is desired.

It will be perceived that, by thus twisting and combining the wires with horizontal rows of rosettes I am enabled to make use of short pieces of wire in the constructing of wire fences, and at the same time to produce a neat, ornamental, and very strong and cheap fence.

I do not claim the design or configuration of the rosettes (B), nor that of the wires between the horizontal twists (A) and the rails (b). Nor that between the twists (A) and the rosettes (B). Nor do I claim the peculiar construction and mode of combination of the ends of the wires, either with the rosettes or with the rails as described, but

What I claim as my invention or production and desire to secure by Letters Patent is, the combination and arrangement of the horizontal twists (A) above and below the rosettes (B), substantially as described and represented in the drawing, forming together (with the wires & rails) an ornamental design for a wire fence, characterized by a horizontal row of rosettes combined with the wires so as to be intermediate or between every two horizontal parallel rows of the horizontal twists.
